UNITED STATES PATENT OFFICE

2,575,134

RADIOACTIVE SOURCE

Warner W. Schultz and Eugene P. Kozoriz, Schenectady, N. Y., assignors to General Electric Company, a corporation of New York

Application December 6, 1950, Serial No. 199,465

3 Claims. (Cl. 250—106)

1

This invention relates to radioactive sources and more particularly to improved leakproof housings therefor.

Wide applications for radioactive sources exist in both medicine and industry, but heretofore these applications have been limited due both to the loss of a large portion of the useful spectrum of radiation in the sources themselves and also to the danger of handling the sources. For example, radium is commonly packed in "needle" form for use in radium therapy, the "needle walls" being made usually of a platinum-iridium alloy. If the walls are made thin enough to allow the softer radiations, i. e., the alpha and beta particles, as well as the gamma rays to escape, the "needles" sooner or later develop dangerous leaks of radioactive material. If the walls are made thick enough to prevent the development of the leaks, they absorb the softer radiations.

It is an object of this invention, therefore, to provide new and improved means for housing a source of radioactivity.

Another object of this invention is to provide a leakproof radioactive source which is simple in construction and low in expense.

A further object of this invention is to provide a radioactive source having a physical barrier of sufficient strength to safely contain the radioactive material yet thin enough to permit the passage of useful radiation.

In accordance with this invention, a deposit of radioactive material is placed on a flat surface of a supporting block formed of a substance, such as metal or resinous material, e. g., fiberglass laminate, which is not readily broken down by prolonged bombardment from radioactive materials. The flat surface and the radioactive layer are covered by a thin sheet of sealing material, such as mica, transparent to the spectrum of radiation from the radioactive material, the sheet of sealing material being bonded to the flat surface by a thin layer of an adhesive agent such as a polyepoxide resin or a low melting glass composition. The supporting block with its radioactive surface and thin covering sheet is placed in a casing made of some material, such as, for example, stainless steel, capable of withstanding prolonged bombardment from nuclear particles and is bonded therein by a layer of adhesive. The casing has an aperture or window over the radioactive portion of the surface to permit the radiations to escape. For further safety, this first casing may be placed within a similar second casing. The second or outer casing has a window con-

2

centric with the window of the inner casing to permit the radiations to escape in the desired direction.

For a better and more complete understanding of this invention, together with additional objects and advantages thereof, reference should now be had to the following description and accompanying drawing, in which:

Fig. 1 is a sectional view, in elevation, of a preferred embodiment of the radioactive source of this invention;

Fig. 2 is a perspective view of a preferred form of the supporting block upon which the radioactive material is deposited;

Fig. 3 shows a preferred manner of depositing the radioactive material on the supporting block shown in Fig. 2; and

Fig. 4 is an enlarged view of a portion of Fig. 1 showing in detail the preferred method of holding the radioactive material on the supporting block.

Referring to Fig. 1, in a housing 1 for a radioactive source, a supporting block 2 contains an annular recess or moat 3 in its flat upper surface 4. Block 2 is formed of a material, such as metal, resins, or laminated fiberglass composed of layers of glass cloth bonded together with a thermosetting resinous composition, which is not readily broken down by prolonged bombardment from radioactive materials. On the portion of surface 4 surrounded by moat 3 is a layer 5 of radioactive material, for example, strontium of atomic weight 90. Lying on surface 4 and extending beyond the edges thereof is a sheet 6 of sealing material, such as mica, which is transparent to the spectrum of radiations from radioactive layer 5. As is shown more clearly in Fig. 4, sheet 6 is bonded to surface 4 by a thin layer 6a of an adhesive or bonding agent, such as, for example, a polyepoxide resin or a low melting glass composition, the lower surface of sheet 6 having been coated with adhesive layer 6a and then pressed against surface 4 as housing 1 was constructed. Adhesive layer 6a also bonds radioactive layer 5 firmly in place.

Disposed on all sides of block 2, except over surface 4, is an inner casing 7. This inner casing 7 is bonded to block 2 by a layer 8 of adhesive and to outer casing 9 by a second layer 10 of adhesive. Outer casing 9 contains aperture 11 over the area in which radioactive layer 5 lies. Outer casing 9 also contains holes 12, through which bolts or screws may be inserted to fasten casing 9 to supporting structure. Casings 7 and 9 are formed of material capable of standing

prolonged bombardment from radioactive materials, such as stainless steel.

In Fig. 2, moat 3 cut in surface 4 of block 2 is shown in perspective. The annular shape of moat 3 is preferred, but other endless shapes, such as rectangles, squares or triangles, may be substituted if desired.

In Fig. 3, one preferred manner of depositing radioactive layer 5 on the portion of surface 4 enclosed by moat 3 is shown. The radioactive material is deposited in solution within the confines of moat 3. Then, the solution is evaporated, leaving radioactive layer 5. During the evaporation process, chimney 13 can be fitted into moat 3 to prevent the spread of radioactivity to other parts of supporting block 2. Other methods of depositing radioactive layer 5 may, of course, be used. Electroplating would be one such method. However, for electroplating to be used, block 2 must be constructed of a conducting material. If electroplating is employed to deposit radioactive layer 5, moat 3 can be eliminated from surface 4, since there is then no evaporation process to offer contamination to surrounding areas.

To continue with the method of constructing housing 1, once radioactive layer 5 is deposited on the portion of surface 4 enclosed by moat 3, a very thin sheet 6 of material is placed over and bonded to surface 4. Sheet 6 must be of such a type that it forms a sealing layer transparent to the useful spectrum of radiation from radioactive layer 5. In the preferred embodiment of this invention, sheet 6 is a sheet of mica but other materials may be employed.

The purpose of sheet 6, as placed over surface 4, is to serve as a barrier to hold radioactive layer 5 thereon, since the escape of any part of layer 5 would present a serious health hazard. The sheet of material must be kept extremely thin where alpha, beta or beta-gamma emitters are employed, in order that the alpha or beta particles will not be absorbed. For low energy gamma or X-ray emitters, the same requirement also exists. Since mica can be split into extremely thin sheets, sometimes even only a few molecules thick, it is an excellent material for this use.

Before sheet 6 is placed on surface 4, the surface of sheet 6 which is to contact surface 4 is coated with adhesive layer 6a. Sheet 6 is then pressed on surface 4, moat 3 acting as a trap for any radioactive material that is squeezed sideways, thus further preventing contamination of any other parts of block 2. The bonding agent not only holds sheet 6 in place, but also by mixing with radioactive layer 5 tends to prevent any movement therein. This is important in that if sheet 6 should be punctured, only the small bit of radioactive material directly underneath the puncture may escape, no matter in what position housing 1 is placed.

This method of depositing radioactive layer 5 within the confines of moat 3 and then bonding it in place with adhesive layer 6a under sheet 6 prevents, as far as possible, the escape of radioactive material in both the construction and use of housing 1. A presently preferred adhesive or bonding agent is a resin of the polyepoxide class. By a polyepoxide resin it is meant any one of the class of thermosetting resins capable of forming large macromolecules, i. e., resins which are capable of becoming highly cross-linked upon polymerization. It is preferable to use a highly cross-linked resin because most other resins lose their physical properties more readily under bom-

bardment from radioactive materials; more specifically, these other resins frequently become friable or turn into powder. The qualities of the polyepoxide resins which make them particularly desirable in this application are that they have no volatile by-products on condensation or polymerization; they have no initial solvents; they set at room temperatures and have a reasonably fast room cure, for example, 4 hours at 70° F. Other preferred adhesive or bonding agents are low melting glass compositions. To be satisfactory, a glass composition must be capable, when liquid, of wetting both surface 4 and sheet 6. It should also have a coefficient of expansion, when solidified, in the order of those of surface 4 and sheet 6 so that appreciable physical stresses will not be set up.

Block 2 with sheet 6 is then placed in inner casing 7 and bonded therein by adhesive layer 8. Casing 7 is, in turn, placed in outer casing 9 and bonded therein by adhesive layer 10. Adhesive layers 8 and 10 are ordinarily formed of the same substance as layer 6a. Casings 7 and 9 are preferably metallic, since metals are extremely good under bombardment. An alloy which is mechanically strong and is quite corrosion-resistant, such as stainless steel, is about the best material which can be used for casings 7 and 9. However, although casings 7 and 9 are preferably metallic their composition is not necessarily restricted to metal. There are a number of non-metallic substances which can stand prolonged bombardment from radioactive materials, and casings which will give satisfactory results can be formed from those non-metallic substances. For example, casings formed of plastics can be substituted for the metallic casings, if desired.

Casings 9 and 11 and block 2 together cut off almost all radiations except those in the desired direction, and, due to the double casing construction, it is almost impossible for radiation leaks to develop, unless housing 1 is severely damaged by some means, such as rough handling.

For some applications, only one casing may be necessary, while in still other applications more than two casings may be desirable. This invention is not to be construed as restricted to a structure having two casings; one casing or a plurality of casings contained one within another may be employed as necessary, the innermost casing, of course, containing the supporting block, the sheet of sealing material and the radioactive deposit contained therebetween.

While there has been described what, at present, is considered to be the preferred embodiment of this invention, it will be obvious to those skilled in the art that various changes and modifications may be made therein without departing from the invention, and it is, therefore, aimed in the appended claims to cover all such changes and modifications as fall within the true spirit and scope of this invention.

What we claim as new and desire to secure by Letters Patent of the United States is:

1. A radioactive source comprising a supporting block formed of a material not readily broken down by prolonged bombardment from radioactive materials and provided with a flat surface; a deposit of a radioactive material on a portion of said flat surface; a thin sheet of sealing material covering said surface and said deposit of radioactive material thereon to form a sealing layer transparent to the spectrum of radiation from said deposit of radioactive material; a layer

of adhesive bonding said sheet of sealing material to said surface; a casing formed of material capable of standing prolonged bombardment from radioactive material containing said supporting block, said sheet of sealing material and said deposit of radioactive material bonded therebetween and having an aperture positioned over said deposit of radioactive material; and a layer of adhesive bonding said supporting block and said sheet of sealing material to said casing.

2. A radioactive source comprising a supporting block formed of a material not readily broken down by prolonged bombardment from radioactive materials and provided with a flat surface containing an endless moat; a deposit of radioactive material on the portion of said flat surface surrounded by said moat; a sheet of sealing material covering said surface and said deposit of radioactive material thereon to form a sealing layer transpartent to the spectrum of radiation from said deposit of radioactive material; a layer of adhesive bonding said sheet of sealing material to said surface; a plurality of casings formed of material capable of standing prolonged bombardment from radioactive materials and contained one within another, the innermost of said casings containing said supporting block, said sheet of sealing material and said deposit of radioactive material contained therebetween, said casings having concentric apertures positioned over said deposit of radioactive material; layers of adhesive bonding said casings to each other, and a layer of adhesive bonding said block and said sheet of material to said innermost casing.

3. A radioactive source comprising a block of

resin-bonded fiberglass laminate provided with a flat surface containing an endless moat; a deposit of radioactive material on the portion of said flat surface surrounded by said moat; a sheet of mica covering said surface and said deposit of radioactive material thereon; a layer of a polyepoxide resin bonding said sheet of mica to said surface; an inner casing and outer casing both formed of material capable of standing prolonged bombardment from radioactive materials, said outer casing containing said inner casing and said inner casing containing said block, said sheet of mica and said deposit of radioactive material contained therebetween, said casings having concentric apertures positioned over said radioactive deposit; a layer of a polyepoxide resin bonding said block and said sheet of mica to said inner casing; and a layer of a polyepoxide resin bonding said inner casing to said outer casing.
